(57) **CLAIM**

The new and original design for an ergonomically contoured adjustable handle for use with multiple heads, as shown and described.

DESCRIPTION

FIG. 1 is a top perspective view of an ergonomically contoured adjustable handle for use with multiple heads showing my new design, said handle being positioned for a left-handed user;

FIG. 2 is a top view thereof;

FIG. 3 is a bottom view thereof;

FIG. 4 is a side view thereof, taken from below FIG. 2;

FIG. 5 is a side view thereof taken from above FIG. 2;

FIG. 6 is an enlarged end view thereof, taken from the left of FIG. 2;

FIG. 7 is an enlarged end view thereof, taken from the right of FIG. 2, showing a leaf rake head as an attachment; and, FIG. 8 is a top view thereof, showing said handle positioned for a right-handed user, showing a leaf rake head as an attachment.

The broken line showing of a rake head is for illustrative purposes only and forms no part of the claimed design.
